UNITED STATES PATENT OFFICE.

CHARLES M. SANDERS, OF GUTHRIE, OKLAHOMA.

NECKTIE-ADJUSTER.

1,302,225.

Specification of Letters Patent. Patented Apr. 29, 1919.

Application filed February 13, 1919. Serial No. 276,757.

To all whom it may concern:

Be it known that I, CHARLES M. SANDERS, a citizen of the United States, residing at Guthrie, in the county of Logan and State 5 of Oklahoma, have invented a new and useful Necktie-Adjuster, of which the following is a specification.

My invention relates to necktie holders and its principal object is to provide a device which will overcome the tendency of the necktie to slip downwardly on the collar and thus expose the collar button.

A further object of the invention is to provide a necktie holder of the above character which will positively retain the tie in position in the collar and at the same time prevent the flaps of the collar moving on the shank of the collar button.

It is another object of the present invention to provide a necktie holder which is neat in appearance and which may be stamped and formed from a single strip of metal.

Another object of the invention resides in 25 the provision of a necktie retaining device which may be readily placed in operative position on the collar and, which will not deface or injure the tie or collar.

An additional object of the invention is to 30 provide a necktie holder which will retain the necktie in a position where the collar button will be hidden from view and which is simple in construction, durable in use, and which may be manufactured and placed on 35 the market at a minimum cost.

The invention consists of constructions, formations, arrangements of parts and general assemblage which will be hereinafter illustrated and described and explicitly de- 40 fined in the subjoined claims.

In the drawing Figure 1 is a fragmentary view of a collar and tie and showing my invention applied thereto.

Fig. 2 is a transverse sectional view of a 45 collar and showing my improved tie holder in operative position.

Fig. 3 is a perspective of the device.

Referring in detail to the drawing, the 50 numeral 5 designates a blank or sheet of metal from which my improved tie holder is formed. This sheet of metal is bent at right angles at 6 and thence bent again at right angles at 7 so as to provide a pair of oppositely extending legs which are offset from 55 each other and extend in parallelism. This

manner of bending the strip 5 affords a substantially Z shaped device. These legs are designated by the numerals 8 and 9.

The part 8 is provided with a V shaped slot 10 which receives the shank of the collar button. The leg 9 extends upwardly from the button. As the leg 8 straddles the collar button at the head of the same and as the leg 9 bears against the knot of the tie it will be manifest that it will be impossible for the 60 device to shift on the shank of the button and that the flaps of the collar are held 65 against movement.

The extremity of the leg 9 is formed with a notch 11 which receives the knot of the tie 70 and thus retains the same in proper position.

From the above disclosure it will be manifest that in order to place the device in operative position it is only necessary to raise 75 the tie after it has been properly tied and adjusted, and engage the shank of the collar button in the slot 10 of the leg 8 and allow the knot of the tie to rest in the notch 11 of the leg 9.

This embodiment of the invention herein 80 described and illustrated is merely for the purpose of illustrating my idea and it is to be understood that the construction may be modified and that my limits of modification are only governed by the subjoined claims. 85

What is claimed is:

1. A tie holder of the character described formed from a strip of metal bent in substantially Z shaped formation, one end of the strip being formed with a slot adapted 90 to receive the shank of the collar button, the opposite end of the strip being provided with a notch for the reception of the knot of the tie.

2. In a tie holder, a strip of metal bent 95 intermediate its ends to afford a pair of parallel oppositely extending legs which are offset from each other, one of the legs being provided with a slot for the reception of a collar button, the remaining leg being provided with a notch adapted to receive the tie.

3. A necktie holder formed from a blank 100 of metal bent at right angles intermediate its ends to provide a collar button engaging leg, the blank being bent again at right angles and extended reversely of the first named leg to afford a tie engaging leg, the button engaging leg and the tie engaging leg being offset from each other, each of the legs being provided with an opening to re- 110

ceive the shank of the collar button and the tie respectively.

4. A neck tie holder formed from a blank of metal bent in substantially Z shaped formation which includes a pair of oppositely extending legs, one of the legs being formed with a V shaped slot for the reception of the shank of the collar button, the first named leg being disposed on the shank 10 of the button, the remaining leg being ar-

ranged to support the tie and also provided with a notch to receive the knot of the tie.

In testimony that I claim the foregoing as my own, I have hereto affixed my signature in the presence of two witnesses.

CHARLES M. SANDERS.
